UNITED STATES PATENT OFFICE.

EDITH SIEGMUND, OF SAN JUAN, PORTO RICO.

DESIGN FOR A DRESS.

Application filed January 14, 1925. Serial No. 12,046. Term of patent 14 years.

To all whom it may concern:

Be it known that I, EDITH SIEGMUND, a citizen of the United States, residing at San Juan, Porto Rico, have invented a new, original, and ornamental Design for Dress, of which the following is a specification, reference being had to the accompanying drawing, forming part thereof, wherein the dress is distinguished by means of two spaced ornamental rectangular inserts A A, located on opposite sides of the front, a pair of ornamental vertical lines B B, located on each side of the neck opening and extending down towards said inserts and formed of openwork, an ornamental series C of vertically-extending and relatively narrow tucks arranged between said inserts A A, an ornamental series D of vertically-extending and

relatively narrow tucks arranged between each pair of ornamental lines B B on each side of the neck opening, an ornamental series E of horizontally-extending and relatively wide tucks arranged below said inserts A A, and an ornamental series F of horizontally-extending lines of openwork alternating with said tucks.

Figure 1 is a front view of a dress showing my design.

Figure 2 is an enlarged fragmentary view showing part of one rectangular insert A, a part of the series C of relatively narrow tucks, and a part of one line B of open-work.

I claim:

The ornamental design for a dress, as shown and described.

EDITH SIEGMUND.
